ABSTRACT OF THE DISCLOSURE

N-penicillanoyloxy derivatives are provided having the formula:

wherein *R* is benzoyl and *R*¹ is phenyl, or *R* and *R*¹ together are alkylidene having 1 to 6 carbon atoms, α -(alkylcarbonyl)alkylidene having 1 to 6 carbon atoms in the alkyl moiety and 1 to 6 carbon atoms in the alkylidene moiety, cycloalkylidene having 3 to 6 carbon atoms, aralkylidene of the formula:

wherein *Z* is *O*, *S* or *N*, benzylidene, succinyl or phthaloyl; and *X* is:

wherein *R*⁵ is phenyl or 2-thienyl;

or *X* is *Y*.CO.NH—, wherein *Y* is benzyl; a 2,6-di(lower-alkoxy)-phenyl group in which each lower alkoxy group is methoxy or ethoxy; a 2-alkoxy-1-naphthyl group in which the alkoxy group has 1 to 4 carbon atoms; a 3,5-disubstituted-4-isoxazolyl group of the formula:

wherein one of *R*⁶ and *R*⁷ is a lower alkyl group of 1 to 4 carbon atoms and the other is

wherein *R*⁸ and *R*⁹ are each hydrogen, chlorine or fluorine; an α -(phenoxy)alkyl group wherein the alkyl group has 1 to 4 carbon atoms; 3-phenyl; 2-phenyl; furfuryl; α -sulphamoyl-benzyl; a group of the formula:

2

wherein *R*¹⁰ is hydrogen or chlorine; α -aminobenzyl; or a group of the formula:

wherein *NRR*¹ is as defined above.

10 This invention relates to penicillin derivatives and is particularly concerned with a novel class of *N*-penicillanoyloxy derivatives.

Many penicillin derivatives are known in which the carboxyl group of the penicillanic acid moiety has been converted to an ester, amide, etc., but such structural modification usually results in a reduction of biological activity against most strains of bacteria.

We have found that the *N*-penicillanoyloxy derivatives of the present invention have the same order of activity against a wide range of bacteria as the parent penicillins from which they were derived.

We have further found that the physical properties of the compounds of the present invention are quite different from those of the usual penicillins and penicillin salts, especially in that their solubility in organic solvents, oils and fats is much greater whereas their solubility in water is much less. Accordingly, the new compounds may be employed in depot therapy (for example by intramuscular injection in admixture or conjunction with pharmaceutically acceptable vehicle), thereby achieving sustained release of antibiotic into the bloodstream over a prolonged period following a single dose.

A further consequence of the increased fat solubility of the new compounds is that certain of them show an enhanced ability to pass through fatty membranes within the animal body. In some cases this results in improved absorption from the gastrointestinal tract into the bloodstream. Again, some of the new derivatives enter and remain within the cerebrospinal fluid more readily than do the conventional penicillin salts.

According to the present invention there are provided penicillanic acid derivatives of the [general] formula:

wherein *R* is an acyl group such as benzoyl and *R*¹ is an aryl group such as phenyl, or *R* and *R*¹ together are [represent] an alkylidene, α -acylalkylidene, cycloalkylidene (e.g., cyclohexylidene), aralkylidene (e.g., benzylidene, substituted benzylidene, or furfurylidene), succinyl

(—COCH₂CH₂CO—)

phthaloyl or substituted phthaloyl radical, and *X* is an acylamino group or a derivative thereof.

60 The group *X* may comprise any side chain which gives an active penicillin. Thus the hydrocarbon portion of *X* may be an aliphatic, arylaliphatic, aromatic or heterocyclic group any of which may be substituted. In the case in which the group *X* is an α -aminoacetamide derivative the two amine functions may be condensed with an aldehyde or ketone to form a cyclic structure of the type:

treated with ethyl chloroformate (1.92 ml.) and dry pyridine (2 drops) and stirred at -5°C . for $\frac{1}{2}$ hour. A solution of $[\alpha\text{-benzaldoxime}]$ $\alpha\text{-benzaldoxime}$ (2.4 g. 0.02 mol) in dry acetone (10 ml.) was added all at once and stirring was continued without further cooling for 2 hours. The product was isolated as in Example 1 to give a hard glass which was ground to a white powder, 1.4 g. (23.4%).

EXAMPLE 8

N(6-phenylacetamido penicillanoyloxy)phthalimide

The mixed anhydride was prepared as in Example 4 from potassium benzylpenicillin and ethylchloroformate and was treated all at once with a solution of N-hydroxyphthalimide (1.63 g. 0.01 mol.) dissolved in warm dry dioxan (10 ml.) and stirred for 2 hours without further cooling. The product was isolated as in Example 1 as a concentrated solution in ethyl acetate. Dilution with dry ether (10 vols.) gave a clear solution which crystallized on standing and scratching. The solid was filtered off, washed with dry ether and dried in vacuo to give 1.83 g. (38.2%) of a colorless crystalline solid M.P. 179–191 $^{\circ}\text{C}$. (d.). Recrystallization from acetone-ether raised the melting point to 185–187 $^{\circ}\text{C}$. (d.). (Found: C, 60.5; H, 4.64; N, 8.87; S, 6.44. $\text{C}_{24}\text{H}_{21}\text{O}_4\text{N}_3\text{S}$ requires C, 60.1; H, 4.42; N, 8.77; S, 6.69%).

EXAMPLE 9

N[6-(2,2-dimethyl-5-oxo-4-phenyl-1-imidazolidinyl) penicillanoyloxy]phthalimide

The mixed anhydride (0.01 mol.) as prepared in Example 2 was treated all at once with a solution of N-hydroxyphthalimide (1.63 g. 0.01 mol.) dissolved in warm dry dioxan (10 ml.) and stirred without further cooling for 2 hours. The product was isolated as in Example 2 to give a non-crystalline solid on dilution with dry ether 2.13 g. (39.8%).

EXAMPLE 10

N(6-phenylacetamido penicillanoyloxy)succinimide

The mixed anhydride (0.01 mol.) as prepared in Example 4 was treated all at once with a solution of N-hydroxysuccinimide (1.15 g. 0.01 mol.) in dry acetone (7 ml.) and stirred for 2 hours without further cooling. The product was isolated as in Example 1 as a thick yellow oil 2.7 g. (62.6%).

EXAMPLE 11

N(6-phenylacetamido penicillanoyloxy) N-phenylbenzamide

The mixed anhydride (0.01 mol.) as prepared in Example 4 was treated, all at once, with N-benzoyl-N-phenylhydroxylamine (2.13 g. 0.01 mol.) in dry dioxan (10 ml.) and stirred for 2 hours without further cooling. The product was isolated as in Example 1 as a brown viscous oil 2.1 g. (39.7%).

EXAMPLE 12

N(6-phenylacetamido penicillanoyloxy)furfurylidene imine

The mixed anhydride (0.01 mol.) as prepared in Example 4 was treated, all at once with a solution of α -furfuradoloxime (1.1 g. 0.01 mol) in dry acetone (5 ml.) and stirred for 2 hours without further cooling. The product was isolated as in Example 1 as a concentrated solution in ethyl acetate. Dilution with dry ether (5 vols.) gave a clear solution which crystallized on addition of a trace of water. The solid was filtered off, washed with dry ether and dried in vacuo to give 2.28 g. (53.4%) of a colorless crystalline solid. M.P. 124–126 $^{\circ}\text{C}$. Recrystallization from acetone/dry ether gave material M.P. 126–128 $^{\circ}\text{C}$. (Found: C, 59.52; H, 4.89; N, 9.84; S, 7.60. $\text{C}_{21}\text{H}_{21}\text{O}_5\text{N}_3\text{S}$ requires: C, 59.0; H, 4.95; N, 9.83; S, 7.50.)

EXAMPLE 13

N[6-(2,6-dimethoxybenzamido)penicillanoyloxy] isopropylidene imine

Sodium 2,6-dimethoxyphenylpenicillin (4.02 g. 0.01 mol.) was converted to the mixed anhydride as in Example 4 and treated all at once with a solution of acetoxime (0.73 g. 0.01 mol.) in dry acetone (5 ml.). The product was isolated as in Example 1 to give a hard glass which was ground to a pale yellow powder 3.9 g. (89.7%).

EXAMPLE 14

N[6-[3-(o-chlorophenyl)5-methyl isoxazole-4-carbonamido]penicillanoyloxy]isopropylidene imine

Sodium 3-(o-chlorophenyl)-5-methyl-4-isoxazolyl penicillin (4.47 g. 0.01 mol) was converted to the mixed anhydride as in Example 4 and treated all at once with a solution of acetoxime (0.73 g. 0.01 mol.) in dry acetone (5 ml.). The reaction mixture was stirred without further cooling for 2 hours. The product was worked up as in Example 1 to give a hard glass which was ground to give a yellow powder 3.25 g. (66.3%).

EXAMPLE 15

N[6-(α -phenoxypropionamido)penicillanoyloxy] isopropylidene imine

Sodium α -phenoxyethylpenicillin (15.44 g. 0.04 mol.) was converted to the mixed anhydride as in Example 4 and treated all at once with a solution of acetone (2.92 g. 0.04 mol.) in dry acetone (20 ml.). The reaction mixture was stirred without further cooling for 2 hours. The product was worked up as in Example 1 to give a pale yellow oil. Trituration of the oil with dry ether caused crystallization to occur. The solid product was filtered off, washed with dry ether and dried in vacuo to give 8.5 g. (50.7%) of a colorless crystalline solid M.P. 115–117 $^{\circ}\text{C}$. (Found: C, 56.98; H, 6.10; N, 9.56; S, 7.56. $\text{C}_{20}\text{H}_{25}\text{O}_5\text{N}_3\text{S}$ requires: C, 57.26; H, 6.01; N, 10.02; S, 7.64.).

EXAMPLE 16

N(6-phenoxyacetamido penicillanoyloxy) isopropylidene imine

Potassium phenoxyethyl penicillin (15.52 g. 0.04 mol.) was converted to the mixed anhydride as in Example 4 and treated all at once with a solution of acetoxime (2.92 g. 0.04 mol.) in dry acetone (20 ml.). The reaction mixture was stirred, without further cooling, for 2 hours. The product was worked up as in Example 1 when the concentrated ethyl acetate solution crystallized. The solid was filtered off, washed with ethyl acetate and dried in vacuo to give 13.2 g. (81.5%) of a colorless crystalline solid M.P. 142–144 $^{\circ}\text{C}$.

EXAMPLE 17

N(6-phenoxyacetamido penicillanoyloxy)benzylidene imine

The mixed anhydride (0.04 mol.) prepared as in Example 16 was treated all at once with a solution of α -benzaldoxime (4.8 g. 0.04 mol.) in dry acetone (20 ml.) and stirred without further cooling for 2 hours. The product was isolated as in Example 1 to give a viscous yellow oil. Trituration of the oil with light petroleum gave a non-crystalline solid 11.4 g. (62.9%).

EXAMPLE 18

N[6-(α -phenoxyproponamido)penicillanoyloxy] benzylidene imine

The mixed anhydride (0.04 mol.) as prepared in Example 15 was treated all at once with a solution of α -benzaldoxime (4.8 g. 0.04 mol.) in dry acetone (20 ml.) and stirred without further cooling for 2 hours. The product, isolated as in Example 1, was obtained as a viscous pale yellow oil. Trituration of the oil with light

7

petroleum gave a white noncrystalline solid 10.7 g. (57.3%).

EXAMPLE 19

N(6-phenylacetamido pencillanoyloxy) α -acetylethylidene imine

The mixed anhydride (0.02 mol.) as prepared in Example 4 was treated all at once with a solution of diacetyl monoxime (2.02 g. 0.02 mol.) in dry acetone (10 ml.) and stirred without further cooling for 2 hours. The product was isolated as in Example 1 to give a brown viscous oil 6.05 g. (72.6%).

EXAMPLE 20

N(6- α -furylacetamido penicillanoyloxy)furfurylidene imine

This was prepared as described in Example 12 except that the mixed anhydride used was prepared from sodium α -furylmethylpenicillin instead of from potassium benzyl penicillin.

EXAMPLE 21

N[6- α -(benzylideneimino oxycarbonyl)3-thienylacetamido penicillanoyloxy]benzylidene imine

This was prepared as described in Example 7 but starting with disodium α -carboxy-3-thienylmethylpenicillin instead of disodium α -carboxybenzylpenicillin.

I claim:

1. N-[6-(2,2-dimethyl - 5 - oxo-4-phenyl-1-imidazolidinyl)penicillanoyloxy]isopropylidene-imine.
2. N-(6 - phenylacetamido - pencillanoyloxy)benzylidene-imine.
3. N-(6 - phenylacetamido - penicillanoyloxy)phthalimide.
4. N-(6 - phenylacetamido - penicillanoyloxy)furfurylidene-imine.
5. N-[6-(2,6 - dimethoxybenzamido)penicillanoyloxy]isopropylidene-imine.
6. N-[6-(α - phenoxypropionamido)penicillanoyloxy]isopropylidene-imine.
7. [An injectable] A compound [suitable for depot therapy] having the formula:

wherein R is benzoyl and R¹ is phenyl, or R and R¹ together are alkylidene having 1 to 6 carbon atoms, α -(alkylcarbonyl)alkylidene having 1 to 6 carbon atoms in the alkyl moiety and 1 to 6 carbon atoms in the alkylidene moiety, cycloalkylidene having 3 to 6 carbon atoms, aralkylidene of the formula:

wherein Z is O, S or N, benzylidene, succinyl or phthaloyl; and X is:

wherein R⁵ is phenyl or 2-thienyl; or X is Y.CO.NH—, wherein Y is benzyl; a 2,6-di(lower-alkoxy)-phenyl group in which each lower alkoxy group is methoxy or ethoxy; a 2-alkoxy-1-naphthyl group in which the alkoxy group has 1 to 4 carbon atoms; a 3,5-disubstituted-4-isoxazolyl group of the formula:

8

wherein one of R⁶ and R⁷ is a lower alkyl group of 1 to 4 carbon atoms and the other is

wherein R⁸ and R⁹ are each hydrogen, chlorine or fluorine; an α -(phenoxy)alkyl group wherein the alkyl group has 1 to 4 carbon atoms; 3-phenyl; 2-phenyl; furfuryl; α -sulphamoylbenzyl; a group of the formula:

where R¹⁰ is hydrogen or chlorine; α -aminobenzyl; or a group of the formula:

wherein NRR¹ is [the same] as [the other —NRR¹ group] defined above.

8. [An injectable] A compound [suitable for depot therapy] having the formula:

wherein R is benzoyl and R¹ is phenyl, or R and R¹ together are alkylidene having 1 to 6 carbon atoms, α -(alkylcarbonyl)alkylidene having 1 to 6 carbon atoms in the alkyl moiety and 1 to 6 carbon atoms in the alkylidene moiety, cycloalkylidene having 3 to 6 carbon atoms, aralkylidene of the formula:

wherein Z is O, S or N, benzylidene, succinyl or phthaloyl; and X is

or Y.CO.NH—, wherein Y is benzyl, 2,6-dimethoxyphenyl; a 3-(substituted phenyl)-5-methyl-4-isoxazolyl group of the formula:

wherein R⁸ and R⁹ are each hydrogen, chlorine or fluorine; α -(phenoxy)-alkyl wherein the alkyl has 1 to 3 carbon atoms; furfuryl; 3-phenyl; α -sulphamoyl-benzyl; or a group of the formula:

wherein NRR¹ is [the same] as [the other NRR¹ group] defined above.

9. [An injectable] A compound [suitable for depot therapy] having the formula:

wherein R is benzoyl and R¹ is phenyl or R and R¹ together are isopropylidene, benzylidene, cyclohexylidene, α -acetylethylidene, furfurylidene, succinyl, or phthaloyl and X is:

or Y.CO.NH—, wherein Y is benzyl; 2,6-dimethoxyphenyl; 3-o-chlorophenyl-5-methyl-4-isoxazolyl; phenoxy-

5

10

yl; α -phenoxyethyl; α -sulphamoylbenzyl; 3-thenyl; furfuryl; or

wherein NRR¹ is [the same] as [the other NRR¹ group] defined above.
